CLAIM

The ornamental design for a connector for device for applying compressive pressure to the leg, as shown and described.

DESCRIPTION

FIG. 1 is a perspective view;
FIG. 2 is a top plan view;
FIG. 3 is a front elevation view;
FIG. 4 is a bottom plan view;
FIG. 5 is a side elevational view thereof, the opposite side elevational view being a mirror image thereto; and,
FIG. 6 is a back elevation view.
